UNITED STATES PATENT OFFICE.

HULBERT H. WARNER, OF ROCHESTER, NEW YORK.

DESIGN FOR A BOTTLE.

SPECIFICATION forming part of Design No. 17,696, dated September 6, 1887.

Application filed April 26, 1887. Serial No. 236,255. Term of patent 14 years.

To all whom it may concern:

Be it known that I, HULBERT H. WARNER, a citizen of the United States, residing at Rochester, in the county of Monroe, State of New York, have invented and produced a new and original Design for a Bottle, of which the following is a specification, reference being had to the accompanying drawings, forming part thereof.

10 The leading features of my design for a bottle are, first, the semi-polygonal form of the body, and, next, the paneled sides thereof.

Figure 1 represents a horizontal section of a bottle embodying my invention, the same being in line x x , Fig. 2. Fig. 2 represents a side elevation thereof.

Similar letters of reference indicate corresponding parts in the two figures.

Referring to the drawings, A represents the 20 body of the bottle, which in cross-section is of polygonal form, or many sides. The front

sides of the body are paneled, the panels being sunken and extending in the vertical direction of the body. The top C of the body, which is also polygonal or many-sided, extends in sloping direction to the neck D. The sides E are curved, but are substantially at a right angle to the back F, the latter being of the width of the bottle. 25

Having thus described my invention, what I claim as new, and desire to secure by Letters Patent, is—

A design for a bottle having a back, F, of the full width of the body, a polygonal front with paneled sides B, the sides E, substantially at right angles to the back, a top, and a neck, as shown and described. 35

HULBERT H. WARNER.
